UNITED STATES PATENT OFFICE.

MARION N. COE, OF MADISON PARISH, LOUISIANA.

IMPROVEMENT IN DEVICES FOR MAKING BALE-TIES.

Specification forming part of Letters Patent No. 121,756, dated December 12, 1871.

To all whom it may concern:

Be it known that I, MARION N. COE, of the parish of Madison and State of Louisiana, have invented a new and useful Implement for Marking Cotton-Bale Ties, consisting of metal bands bound around the bale; and I do hereby declare that the following is a full, clear, and exact description thereof, which will enable others skilled in the art to make and use the same, reference being had to the accompanying drawing forming a part of this specification, in which—

Figure 1 is a side elevation, and Fig. 2 is a plan of the same; Fig. 3, a front elevation of the stock; Fig. 4, a plan of type-holder; Fig. 5, a plan of type.

A indicates a spring; B, a handle. C is a pointed tongue, dart-shaped, and beveled on the lower side, as shown, so as to be easily forced under the band, having a shoulder at D, which serves as a gauge or stop. The upper surface of this tongue is flat, and it must be thick enough in that part which comes under the stamp to sustain the shock of a sharp blow upon the stock. G. G, a stock, secured to the end of arm E by thumb-screw H; said stock has a dovetailed chamber at its lower end to receive a plate, I; this plate has a long narrow hole through its thinnest way to receive types or blocks J. These

blocks, containing letters, figures, ciphers, or characters, are separate, so as to admit of being taken out and replaced when they become worn, or whenever desired to change the name or figures.

In practice the handle of stamp is taken in the hand and the dart-shaped point forced under the ties which extend around the bales; when the stock containing the stamp, which is always raised by a spring when not in use, is depressed with sufficient force to print the characters permanently upon the tie.

When stamped in this manner the marks cannot be effectually erased, and thereby prevents the probability of the loss of bales by either stealing or wrong shipment.

What I claim as my invention, and desire to secure by Letters Patent, is—

The combination of the handle B, hinged arm E, stock G for holding the type-block, spring A, and the beveled and dart-shaped tongue C, all constructed and arranged to operate substantially as described.

MARION N. COE.
